UNITED STATES PATENT OFFICE.

ALFRED E. SEELIG AND VICTOR H. CARPLES, OF NEW YORK, N. Y.

AIR-BLOWING DEVICE.

1,408,715.

Specification of Letters Patent. Patented Mar. 7, 1922.

Application filed February 24, 1919. Serial No. 278,895.

To all whom it may concern:

Be it known that we, ALFRED E. SEELIG and VICTOR H. CARPLES, citizens of the United States, and residents of the borough of Manhattan, in the city of New York, county of New York, and State of New York, have invented certain new and useful Improvements in Air-Blowing Devices, of which the following is a specification.

This invention relates generally to air blowing devices, and more particularly to that type of blower in which the effective peripheral portion of the blade creates a hollow column of air substantially parallel to its axis; such blowers being generally known as helical fans or fans of the screw propeller type. Current producing devices of this general nature operate with a comparatively high degree of efficiency but it has been found that the rotation of the fan has the effect of producing a movement not only in the desired direction along the axis of the pipe but also a radial and outward component of motion and, in addition, a rotating or swirling motion of the current of air that is passing through the pipe. It will be obvious that the swirling motion thus given to the moving column of air detracts from the general efficiency of operation of the device, since the rotary component of motion serves no useful purpose, but renders ineffective a part of the whole energy of motion of the air current that should be wholly directed in a useful direction toward the outlet end of the pipe. It has been further found that the creation of a radial component results in the formation of eddy currents that swirl backward from the current issuing from the fan into the fan center where they interfere with the normal operation of the device. A further obstacle is found in the fact that the radial component adjacent the intake side of the fan is thrown suddenly and violently outwardly and that the blast of air created is a hollow column that tends to impinge on the walls of the pipe thereby retarding movement of the fan blades, and which is somehow reformed into a solid column of air filling the pipe. The main object of this invention is to provide an air blowing device of the character set forth in which the radial component created adjacent the intake side of the fan shall be gradually directed in an outward

direction and then in a direction substantially parallel to the axis of rotation of the fan; and in which the hollow column of air issuing from the discharge side of the fan will not appreciably impinge against the walls of the pipe but will be gradually restored to a solid column, free of swirling motion and eddy currents and traveling in a direction parallel to the axis of rotation of the fan.

In accordance with the above the invention resides in the features of construction, combination of parts and arrangement of elements hereinafter set forth and claimed.

In the accompanying drawings the invention is disclosed in several concrete and preferred forms in which—

Figure 1 is a longitudinal sectional view, largely diagrammatic in character, of a device embodying the invention in one form.

Figure 2 is a view similar to Fig. 1 with one of the fan blades in section showing a modified form of the invention.

Figure 3 is a view in perspective of the anti-swirling device, looking into the outlet end thereof, and adjacent elements, the pipe being indicated by a ring.

Figure 4 is a view in perspective of the anti-swirling device, looking into the inlet end thereof, and adjacent elements, the pipe also being indicated by a ring.

Figure 5 is a sectional view on line 5—5 of Fig. 1 showing the anti-swirling device in elevation.

Figure 6 is a perspective view of the fan and air guiding member at the intake side of the fan.

1 indicates a fan of the helical or screw propeller type, that is of such a character as to produce a hollow column of air at the effective peripheral portion 11 of its blades in a direction substantially parallel to its axis and lengthwise of the casing or pipe

2. To gradually direct the incoming air toward the effective peripheral portion of the blades there is provided a central air guiding member 6 that rotates with the fan, is of less diameter than the latter and is disposed in rear of cutting edges 12 of the fan blades substantially throughout their length, said member having a surface 13, as shown, facing in the same direction as the intake side of the fan and a second surface 14 merging with the first surface ad-

adjacent the effective peripheral portion of the fan for directing the air current in a direction substantially parallel to the axis of rotation adjacent the discharge side of the fan.

5 The surfaces 13 and 14 may also be considered as one surface of substantially ogee-shape. A convenient construction is shown in the drawings in which member 6 is provided with slits 15 for the reception of the 10 fan blades and suitable means, as screws 16, may be employed to secure said member to the hub of the fan. Member 6 may terminate flush with the discharge side of the fan or may extend slightly beyond that point 15 as shown in Fig. 6.

Adjacent the discharge side of the fan and preferably beyond the plane of the blades is an air directing member 8 for gradually permitting the hollow column of air to reform into a solid column moving in a direction parallel to the axis of rotation. Member 8 is of a diameter substantially equal to that of member 6 at the point where their edges meet and said members are axially co-25 incident and are arranged back to back with their directing surfaces facing away from each other. Preferably member 8 has an ogee-shaped surface, as shown, facing in the same direction as the discharge side of the fan. Members 6 and 8 may be one member and may both rotate with the fan, but preferably 30 8 is a stationary member with its back as closely adjacent the fan blades or as closely adjacent the back of member 6 as 35 possible.

Adjacent the discharge side of the fan is an anti-swirling device 3 whose function it is to translate the swirling component of the air current into one substantially parallel to the axis of rotation. This device 40 consists of a number of stationary blades as shown projecting from the member 8, said blades meeting the swirling air and having substantially helical surfaces 4 at their intake sides which surfaces gradually change their direction until they become straight surfaces 5 at the outlet side of the device.

In order to prevent the current of air created by the fan blades from impinging 50 against the wall of the pipe or casing, and thus interfering with the efficient rotation of the fan by creating eddy currents, it is preferred to bend or curve the outer edge of the fan blades toward the outlet side of fan as at 7 (Fig. 2).

It will be understood from the foregoing that the air is gradually guided from the central portion of the fan toward the periphery thereof and thence in the form of a 60 hollow column in a direction parallel to the axis of rotation; and that the discharge air is prevented from impinging against the wall of the casing, is gradually restored to a solid column and has its swirling component eliminated. This tends to increase the 65

efficiency of the fan by avoiding unnecessary friction losses and preventing eddy currents and blow backs.

We claim:

1. An air blowing device comprising: a 70 pipe, a fan having blades the effective peripheral portion of which creates a hollow column of air parallel to the axis of rotation of the fan and lengthwise of the pipe, said column of air being composed of a plurality 75 of components one of which is parallel with the axis of rotation of the fan, another of which is radial with respect thereto and a third of which is swirling in character, means rotating with the fan for preventing 80 the radial air component from impinging against the wall of the pipe by directing it lengthwise thereof, stationary means at the outlet side of the fan and in the path of the air current for gradually translating the 85 swirling component of the air current into one acting in a line substantially parallel to the axis of rotation of the fan, and means at the outlet side of the fan for gradually translating the hollow column of air into 90 a solid stream.

2. An air blowing device comprising: a fan having blades the effective peripheral portion of which creates a hollow column of air substantially parallel to its axis, and a central air guiding member rotating with the fan of less diameter than the latter and disposed in rear of the cutting edges of the blades substantially throughout their length, 95 said member having a surface facing in 100 the same direction as the intake side of fan of a contour to gradually direct the incoming air toward the effective peripheral portion of the fan, and a second surface on said member adjacent the effective peripheral 105 portion of the fan merging with the first surface and directing the air current in a direction substantially parallel to the axis of rotation adjacent the discharge side of the fan.

3. An air blowing device comprising: a fan having blades the effective peripheral portion of which creates a hollow column of air substantially parallel to its axis, and a central air guiding member rotating with 115 the fan of less diameter than the latter and disposed in rear of the cutting edges of the blades substantially throughout their length, said member having a substantially ogee-shaped surface facing in the same direction 120 as the intake side of the fan to gradually direct the incoming air toward the effective peripheral portion of the fan and then in a direction substantially parallel to the axis of rotation of the fan.

4. An air blowing device comprising: a fan having blades the effective peripheral portion of which creates a hollow column of air substantially parallel to its axis, and a central air guiding member of less diameter 125

than the fan at the discharge side of said fan, said member having a substantially ogee-shaped surface extending away from the discharge side of the fan to gradually direct the air into a solid column parallel to the axis of rotation of the fan.

5. An air blowing device comprising: a fan having blades the effective peripheral portion of which creates a hollow column of air substantially parallel to its axis, a central air guiding member rotating with the fan, of less diameter than the latter and disposed in rear of the cutting edges of the blades substantially throughout their length, 10 said member having a surface facing in the same direction as the intake side of the fan of a contour to gradually direct the incoming air toward the effective peripheral portion of the fan and then substantially parallel to the axis of the rotation adjacent the discharge side of the fan, and a central air 15 guiding member at the discharge side of the fan having a surface extending away from the discharge side of the fan to gradually direct the air into a solid column parallel to the axis of rotation of the fan, said guiding members being axially coincident and arranged back to back with their edges adjacent and of substantially equal diameter 20 to form a substantially continuous opening 25 for the passage of air.

6. An air blowing device comprising: a fan having blades the effective peripheral portion of which creates a hollow column of air substantially parallel to its axis, a central air guiding member rotating with the fan, of less diameter than the latter and disposed in rear of the cutting edges of the blades substantially throughout their length, and 30 a central air guiding member at the discharge side of the fan, said guiding members being axially coincident and arranged back to back with their edges adjacent and of substantially equal diameter to form a 35 substantially continuous opening for the

passage of air, and said members having oppositely disposed substantially ogee-shaped surfaces to direct the incoming air outwardly at the intake side toward the peripheral portion of the fan and inwardly at the discharge side into a solid column substantially parallel with the axis of rotation of the fan.

7. An air blowing device comprising: a fan having blades the effective peripheral portion of which creates a hollow column of air substantially parallel to its axis, a central air guiding member rotating with the fan, of less diameter than the latter and disposed at the intake side thereof, and a central air 50 guiding member at the discharge side of the fan, said guiding members being axially coincident and arranged back to back with their edges adjacent and of substantially equal diameter to form a substantially continuous opening for the passage of air, and said members having surfaces to direct the incoming air outwardly at the intake side toward the peripheral portion of the fan, and inwardly at the discharge side into a 55 solid column substantially parallel with the axis of rotation of the fan.

8. An air blowing device comprising: a fan having blades the effective peripheral portion of which creates a hollow column of air substantially parallel to its axis, an air guiding member facing in the same direction as the intake side of the fan disposed in the plane of the blades for gradually directing the air outwardly toward the effective peripheral portion, and a second air guiding member facing in the same direction as the discharge side of the fan located beyond the plane of the blades at the 60 said discharge side.

Signed at New York city, in the county of New York and State of New York, this 20th day of February, 1919.

ALFRED E. SEELIG.
VICTOR H. CARPLES.
